UNITED STATES PATENT OFFICE.

AUGUSTINE BREESE, OF ADRIAN, MISSOURI.

VENTILATING APPARATUS.

No. 905,283.

Specification of Letters Patent.

Patented Dec. 1, 1908.

Application filed November 9, 1907. Serial No. 401,485.

To all whom it may concern:

Be it known that I, AUGUSTINE BREESE, citizen of the United States, residing at Adrian, in the county of Bates and State of Missouri, have invented certain new and useful Improvements in Ventilating Apparatus, of which the following is a specification.

This invention comprehends certain new and useful improvements in ventilating apparatus, the present embodiment of the invention being illustrated in connection with a railway car or coach, and the invention has for its object an improved construction of apparatus of this character, designed to maintain a proper temperature, to furnish fresh and purified air to the occupants and to absorb or carry off the vitiated air as fresh air is supplied.

With these and other objects in view as will more fully appear as the description proceeds, the invention consists in certain constructions, arrangements and combinations of the parts that will be hereinafter fully described and claimed.

For a full understanding of the invention, reference is to be had to the following description and accompanying drawings, in which:

Figure 1 is a longitudinal sectional view of my improved ventilating apparatus, with parts in side elevation; Fig. 2 is a transverse sectional view with parts in elevation; and, Figs. 3 and 4 are detail views illustrating different forms of distributers or radiators for the fresh air.

Corresponding and like parts are referred to in the following description and indicated in all the views of the drawings by the same reference characters.

Referring to the drawings, the numeral 1 designates an intake for the fresh air, said intake being in the form of a horizontally disposed bell or funnel mounted to turn about a horizontal axis above the roof of the car and supported on the fresh air supply pipe 2 which extends downwardly from the intake in the car and which is connected at its lower end to a suction fan 3 which may be of any desired construction, design and capacity, according to the requirements of the particular case, and which is preferably mounted in the lobby at one end of the car. The outlet pipe 4 of the fan is connected to the lower end of a preferably vertically disposed water receptacle 5. This water re-

ceptacle is provided with a series of superposed diaphragms 6 that may be formed of wire mesh, and it contains a predetermined amount of water. The outlet pipe 4 of the fan is connected at its outer end to a rose or similar distributing device 7 designed to distribute air as it passes through the water in the receptacle 5. Preferably the uppermost diaphragm 6 is covered with a comparatively heavy mat of canvas or similar loose mesh fabric, as indicated at 8, designed to prevent the ebullition of the air as it issues from the water.

The air reservoir 9 is suitably mounted in the car and is connected to the water receptacle 5 in such a manner as to receive the air from the latter after the air has been purified and entirely freed from dust particles or cinders, or the like, by passing through the water in the receptacle 5. The pipe 10 which conveys the purified air into the reservoir 9 preferably extends over the bottom of the reservoir in the shape of a coil, as indicated at 11, and the said reservoir may contain ice or any other suitable refrigerant in summer or be heated in any desired way in winter, so as to maintain the air at the proper temperature, say, seventy degrees. Fresh air discharge pipes 12 are connected to the air reservoir 9 and preferably extend downwardly therefrom and along both sides of the car, in juxtaposition to the berths or seats of the car, and at predetermined intervals, say, at every berth or seat. If desired, said fresh air discharge pipes are provided with distributing outlets 13 or radiators intended to spread out the air over a considerable surface, as it issues from the discharge pipes 12. If desired, as illustrated in Fig. 4, these distributing radiators may be in the form of rotary fans, as indicated at 13^a, said fans being actuated by the force of the air passing through the discharge pipes.

In order to exhaust the vitiated air from the car, I provide exhaust pipes 14 that are preferably arranged along the sides of the car near the roof and that are provided with inlet or suction openings 15. The pipes 14 are connected to an exhaust fan 16 preferably mounted in the end of the car opposite the fan 3 and provided with an outlet pipe 17 extending downwardly through the floor of the car. It is to be understood that the fans 3 and 16 may be operated by electric motors (not shown) or by driving connec-

tion with the axles of the car, or in any other suitable way and that both fans are of about the same capacity so that the air will be exhausted at the same speed or volume 5 that it is fed into the car.

The water receptacle 5 is provided with a drain pipe 18 extending downwardly through the floor of the car, so that, by opening said drain pipe, the water may be forced 10 out by the fan 3 and thereby effectively clean the water receptacle. The water receptacle is provided with a removable top 19 so that fresh water may be introduced therein.

By mounting the intake funnel or bell in 15 a revoluble manner upon the upper end of the fresh air supply pipe 2, the position of said intake may be changed either towards the rear or front of the car, as desired, on account of rain, or wind, or dust storms.

20 From the foregoing description in connection with the accompanying drawings, it will be seen that I have provided an improved construction of ventilating apparatus, by the use of which the air is purified before it enters the coach and is free from dust and cinders, and is maintained at the proper temperature, both summer and winter, and evenly distributed so that each occupant will have an equal share of uncontaminated air. 25 As the vitiated air is carried out as fast as it is contaminated, safety from infection is insured, and as pressure is kept constant, there will be no drafts or sudden changes of temperature, and there will be no necessity 30 of opening or closing any of the windows or doors to secure the proper ventilation.

35 While I have herein described and illus-

trated my improved ventilating apparatus as embodied in a railway coach, it is to be understood that the invention is equally applicable for use in the rooms of dwellings, schools, churches, or the like, and that various changes may be made in the proportions, constructions and arrangements of the parts, within the scope of the appended claim, according to the particular requirements of the compartment in which the invention is installed.

Having thus described the invention, what is claimed as new is:

An apparatus of the character described, comprising a suction fan, a fresh air pipe leading into the fan, a water receptacle operatively connected to the fan, a plurality of diaphragms extending entirely across the water receptacle and spaced one above the other all of the said diaphragms being submerged, another diaphragm above said first named diaphragms and above the level of the water in the receptacle, said last named diaphragm being provided with a porous mat, the connection between the fan and the receptacle extending into the bottom of the receptacle below all of the diaphragms and provided with a rose or distributing device and air discharge pipes connected with the receptacle above the diaphragms.

In testimony whereof I affix my signature in presence of two witnesses.

AUGUSTINE BREESE. [L.S.]
